UNITED STATES PATENT OFFICE

CHARLES W. CARR, OF MEADOW GROVE, NEBRASKA

VALVE-SPRING LIFTER

Application filed September 27, 1928. Serial No. 308,704.

The invention relates to pushing and pulling devices and more particularly to a jack structure which is herein disclosed as forming part of a valve spring lifter.

It is the principal object of the invention to provide a construction of simplified and improved nature for use primarily in spring lifters of the general type shown in my U. S. Patent No. 1,607,866 of November 23, 1926.

With the foregoing in view, the invention resides in the novel subject matter herein-after described and claimed, description being accomplished by reference to the accompanying drawings.

Fig. 1 is a perspective view.

Fig. 2 is an enlarged fragmentary vertical section, partly in elevation, showing the work-performing dog and the holding dog in operative engagement with the teeth of the shank.

Fig. 3 is a view similar to Fig. 2 but illustrating the manner in which the maximum upward movement of the operating lever effects release of both dogs.

Fig. 4 is a horizontal sectional view on line 4—4 of Fig. 2.

The drawings above briefly described illustrate the preferred form of construction and while this construction will be herein specifically explained, it is to be understood that within the scope of the invention as claimed, variations may be made.

The numeral 5 denotes a vertical shank having longitudinally spaced ratchet teeth 6 on one edge. The lower end of this shank is provided with a lateral foot 7 adjustably received in the channel of a lower channel-shaped arm 8, the foot and arm being connected by cotter pins 9 passed through openings. A plurality of these openings indicated at 10, are provided in the side flanges of the arm 8 to permit adjustment of the latter. Received in the outer end portion of the arm 8, is a short bar 11 which projects from a valve spring-engaging fork 12, said arm and

bar being connected by a cotter pin 13 passing through openings. The bar 11 is preferably formed with a plurality of these openings denoted at 14, permitting adjustment as occasion may demand.

A slide S of novel construction is mounted upon the shank 5 and by means of a hand lever 15 and dogs hereinafter described, the slide and shank may be relatively moved. Slide S is provided with a channel-shaped arm 16 spaced above the arm 8, and an inverted L-shaped, valve-holding member 17 is adjustably mounted in the outer end of said arm 16, by means of a cotter pin 18 passing through openings, some of which are indicated at 19. Member 17 is adapted to hold a valve of an internal combustion engine against ascent, while the shank 5 is being raised to cause the fork 12 to compress the valve spring.

In the present showing, the slide S embodies two flat, vertically elongated, stamped metal plates 20 each of frame-like form and embodying two parallel vertical portions 21—22, an upper end portion 23 and a lower end portion 24. The two vertical portions 21 of the plates are secured to each other by rivets 25 and some of these rivets preferably pass through the inner end of the arm 16 to secure it to the slide. Other rivets 26 secure the vertical portions 22 against each other and these portions and the portions 21 form composite vertical bars disposed at the inner and outer edges of the shank 5; the bar 21—22 being outwardly spaced from the teeth 6. The end portions 23—24 of the plates 20 are spaced apart to provide upper and lower yokes which slidably receive the shank 5.

Between the upper rear corners of the plate portions 23 adjacent the teeth 6, a holding dog 27 is pivoted. The pivot of this dog is shown at 28 and this pivot is near the upper end of the dog, which end engages the teeth 6. The lower end of the dog projects down-

wardly in outwardly spaced relation with the composite bar 22—22 and constitutes a tail 29. A suitable spring 30 is provided for engaging the dog 27 with the teeth 6. This 5 spring is preferably received at its inner end in a socket 31 formed in a block 32 which is secured by rivets 33 between the rear ends of the plate portions 23, and displacement of the outer end of the spring may be prevented by 10 a stud 34 on the dog 27.

The rear ends of the plate portions 24 are provided with laterally spaced lugs 35 between which the lower end of a short vertical link 36 is pivoted at 37. The lever 15 is provided with two arms 38 which straddle the upper end of the link 36 and the composite bar 22—22, said arms being pivoted to the link at 39. Between the free ends of the arms 38 and located between the shank 5 and the composite bar 22, is a work-performing dog 40. Between its ends, this dog is pivoted at 41 to the arms 38, and an appropriate spring device 42 acts against the dog 40 and re-acts against the composite bar 22—22, to engage 20 said dog with the teeth 6. In the angle between the composite bar 22—22 and the lower yoke 24—24, the former is provided with cam portions 43 adapted to strike the lower end of the dog 40 upon maximum upward movement 30 of the lever 15, so as to at that time effect release of said dog as shown in Fig. 3. Lever 15 is provided between the arms 38 with a shoulder 44 which strikes the tail 29 of the dog 27 at the same time the dog 40 strikes the 35 cams 43, and at this time said shoulder effects release of said dog 27. Thus, while the slide S and the shank 5 may be relatively moved to compress the valve spring, by oscillation of the lever 15, upward swinging of this lever to the maximum will immediately effect release 40 of both dogs 27—40, thereby allowing the tool to be quickly and easily removed. Moreover, this capability of the tool, allows it to be quickly and easily opened to the maximum 45 for initial engagement with the work.

On account of the excellent results obtainable from the details disclosed, they are preferably followed. However, as above stated, variations may be made within the scope of 50 the invention as claimed.

I claim:—

1. In a device of the class described, a shank having longitudinally spaced teeth, a slide on said shank, a lever mounted on 55 said slide and having a work-performing dog engageable with said teeth, and a holding dog also mounted on said slide and engageable with said teeth, said slide having a portion to strike and release said work-performing dog when the lever is moved to one extreme position, said lever being provided with a portion to then strike and release said holding dog.

2. In a device of the class described, a shank having longitudinally spaced teeth;

a slide embodying upper and lower yokes surrounding said shank, and a bar connecting said yokes and spaced outwardly from the toothed edge of said shank; a lever mounted on the slide and having two arms straddling said bar, a work-performing dog between said bar and said shank and pivoted between its ends between the front ends of said arms, the upper end of said dog being engageable with said teeth, and a holding dog pivoted to the upper yoke and engageable at its upper end with said teeth, said holding dog having a downwardly projecting tail spaced outwardly from said bar, said slide having a portion to strike the lower end of said work-performing dog and release the latter when the lever is raised to the maximum, said lever having a portion to then strike said tail of the holding dog and release the latter.

3. In a device of the class described, a shank having longitudinally spaced teeth; a slide embodying upper and lower yokes surrounding said shank, and a bar connecting said yokes and spaced outwardly from the toothed edge of said shank, the lower end of said bar being provided with a lug, a short vertical link pivoted at its lower end to said lug, a lever having two arms which straddle the upper end of said link and said bar, a fulcrum connecting said arms with said link, a work-performing dog between said bar and said shank and pivoted between its ends between the front ends of said arms, the upper end of said dog being engageable with said teeth, and a holding dog pivoted to the upper yoke and engageable at its upper end with said teeth, said holding dog having a downwardly projecting tail spaced outwardly from said bar, said slide having a portion to strike the lower end of said work-performing dog and release the latter when the lever is raised to the maximum, said lever having a portion to then strike said tail of the holding dog and release the latter.

4. In a device of the class described, two opposed vertically elongated metal plates each of frame-like form and embodying two parallel vertical portions and upper and lower end portions, the vertical portions of the two plates being secured together to provide vertical composite bars while said end portions of said plates are spaced apart to provide upper and lower yokes, a holding dog pivoted between two upper corners of said plates and having a tail projecting downwardly at the outer edge of one of said composite bars, the plate corners at the lower end of this bar being provided with laterally spaced lugs, a short vertical link whose lower end is pivoted between said lugs, a lever having two arms straddling the upper end of said link and said one composite bar and fulcrumed to the former, a work-per-

forming dog pivotally mounted between the free ends of said arms at the inner edge of said one of said composite bars, this inner bar edge being provided with a cam portion to strike the lower end of the work-performing dog and release the latter upon maximum upward swinging of the lever, said lever being provided with a portion to then strike said tail of the holding dog and release the latter, and a shank passing through said yokes and having teeth co-acting with said dogs.

In testimony whereof I have hereunto affixed my signature.
